TO THE FESSENDEN-ELLIS COMPANY, OF SHEBOYGAN, WISCONSIN, A CORPOR-
ATION OF WISCONSIN.

AUTOMATIC DRAFT REGULATOR FOR FURNACES.

Application filed August 8, 1921. Serial No. 490,631.

To all whom it may concern:

Be it known that we, LOUIS P. FESSEN-
DEN and HARRY R. ELLIS, citizens of the
United States, residing at Sheboygan, in
5 the county of Sheboygan and State of Wis-
consin, have invented new and useful Im-
provements in Automatic Draft Regula-
tors for Furnaces, of which the following
is a specification.

10 This regulator is designed to regulate the
pressure over the fire in the combustion
space of a forced draft stoker installation
as generally applied to steam boilers, where
the air for the combustion of the fuel is
15 furnished under pressure to the under side
of the fuel bed and the products of combus-
tion are carried away from the draft or
suction furnished usually by a chimney or
stack, although this function is sometimes
20 taken care of by what is known as an in-
duced-draft fan. In this description we
will assume the draft is furnished by a
stack although the regulator is equally ap-
plicable to the control of an induced-draft
25 fan. In an installation like that described,
the undergrate supply of air is regulated
usually by varying the speed of the blower
by a regulator which responds to variations
30 in the steam header pressure, and there are
many different makes of such regulators,
that give very satisfactory results.

From an economical standpoint both as
to quantity of fuel consumed and the
maintenance of the furnaces and boilers,
35 the proper draft to be carried over the fire
has been found to be just enough below
atmospheric pressure as to carry the prod-
ucts of combustion up the stack, rather
than to force them out into the fireroom.
40 To maintain such a slight draft, with a
fuel bed ever tending to change its thick-
ness, due to various sizes and quality of
fuel and an undergrate pressure varying
45 with the changes in demand for steam, re-
quires a regulator of great sensitiveness.
Many attempts have been made to regulate
this over-fire draft by regulators function-
ing from the header pressure, but as no
50 relation exists between the two they have
not proven successful, so that in most cases,
the uptake damper is set in such a position
that at full blower pressure, there will
be draft enough maintained by the stack to
carry away the products of combustion

without putting pressure above atmosphere 55
in the combustion space, and with the in-
evitable result that at all other blower pres-
sures there is too much draft accompanied
by loss in economy of fuel and maintenance
60 of furnaces due to infiltration of air.

In order that the invention may be better
understood, reference is had to the accom-
panying drawing, forming a part of this
specification, in which;

Figure 1 is an elevation of the apparatus 65
partly in section, and Fig. 2 is an enlarged
elevation of a compensating device.

As the pressure to be regulated is the
pressure in the combustion space 18 of a
furnace, that pressure is made use of to 70
move a freely suspended inverted cap or
cylinder 2 open on its lower end, in a
container 1 which is partly filled with oil,
water or any other liquid to form a seal
between the pressure which exists under the 75
cylinder 2 through connecting pipe 3 which
goes to that part of furnace combustion
space 18 wherein the pressure is to be regu-
lated. Container 1 has a cored passage 22
from a point where connecting pipe 3 is 80
attached which conveys the pressure exist-
ing in the-furnace combustion space 18 to
the area above the water seal in cylinder
1. The top side of cylinder head is acted
upon by the atmospheric pressure of the 85
surrounding air. Cylinder 2 is connected
by a flexible or other connection 4 to a
balance beam 5 which is fulcrumed on a
bracket 6 by a knife edge 23 and carries
a weight pan 8 which latter, as well as the 90
connection 4 are also suspended on knife
edges so as to make the balance beam 5
practically frictionless. Balance beam 5
also carries a slidale poise 7 to assist in
the finer adjustment of balance. Operat- 95
ing cylinder 11 and pilot valve 10 are well-
known commercial devices used in connec-
tion with various automatic mechanisms and
their action is so well understood that it is
not necessary to describe the same in detail 100
except as it may be necessary to refer to their
action in connection with the present ap-
paratus. The pilot valve 10 is connected
to balance beam 5 through a ball-and-socket
connection 9 inserted in valve stem of the 105
pilot valve 10 to render its action as fric-
tionless as possible due to any misalign-
ment and also because the motion derived

from the beam 5 is not a straight line motion. Connection is made with plunger rod of operating cylinder 11 and damper lever 14 by any of the usual means, as a chain, 5 wire, rope or rods, as shown at 13. Damper 15 is counter-balanced to close by a weight 17 when a flexible connection is used to connect the regulator and the lever 14.

The operation of the apparatus is as follows:

Connection 13 is adjusted so that upon maximum travel of plunger 12 of operating cylinder 11, the damper 15 will travel from full open to full shut position or whatever 10 part of that travel may be deemed necessary. The weight on balance beam 5 are so adjusted that when pressure in combustion space 18 is that which it is desired to maintain, balance beam 5 will be in horizontal position 15 and at rest. In this position cylinder 2 should be in mid-position of its travel in container 1 and valve stem 9 should be so adjusted that there will be no movement of plunger 12. This condition of rest will 20 continue as long as the pressure in combustion space 18 does not tend to change. But a very slight change in this combustion space pressure will cause cylinder 2 to move up or down, down for a decrease in pressure and 25 up for an increase, thereby moving balance arm 5 correspondingly, and through it causing pilot valve 10 to admit fluid to one side or the other of plunger 12 in cylinder 11, which in turn moves damper 15 to a position 30 where all parts will again be at rest with the pressure in combustion space 18 at its predetermined value.

In practice it was found that, due to a small time interval between the time the 40 damper moves and the reestablishment of the predetermined pressure in combustion space, a hunting action of regulator would be set up, and while the predetermined pressure would be held very close, the regulator 45 would be kept in motion continuously. This hunting action is taken care of by a compensating device, which is very simple, but a valuable part of the invention. It consists of two springs which may be applied to 50 balance beam 5 either side of fulcrum point 23 so that when balance beam 5 is at rest in its neutral position, which is horizontal, no pressure is exerted by springs on the beam. Any movement of beam 5 in either 55 direction however is resisted by a constantly increasing pressure of the spring which opposes it in the direction it tends to move. By adjusting tension in these springs any desired amount of compensation can be attained 60 and the aforementioned lag or time element in change of furnace pressure is overcome and hunting action of the regulator obviated. The drawing shows these springs 19 as flat springs mounted on suitable support, 65 their free ends, bearing on balance beam 5.

The counter balance system comprising the beam 5 with its counter weights 7 and 8 on one side of the fulcrum 23 and the weight of the cup or piston 2 on the other side of the fulcrum has a natural period of vibration, which is not secured by the balancing 70 springs 19, since they are resilient and do not dissipate energy but merely return it to the system. The damping out of the periodic or natural vibration of the system is 75 performed by the bell or cup 2 and its liquid seal in the chamber 1, which thus performs the dual function of a piston and also of a dash pot.

The prevention of hunting of the regulator is a different problem. The springs 19 secure the function of preventing hunting by providing a resistance increasing with deflection operating in conjunction with the valve 9, which admits fluid more rapidly to the working cylinder for increased deflection of the beam. Thus the response is graduated to conform to the intensity of the disturbance and hence overthrow with consequent 80 hunting does not occur.

We do not confine ourselves to this particular construction as many modifications in the application of a spring or springs to do the same thing might be evolved.

As the position of plunger 12 and damper 15 is an indication of the volume of gases passing through boiler gas passages and thus of the demand on boiler for steam, advantage is taken of this relation to control the speed of stoker engines and thereby the quantity of and time of feeding fuel to furnace. This is accomplished by connecting stoker control valve 21 by a flexible connection 20 to plunger 12 and adjusting it so that with plunger at extreme top of its travel in cylinder 11, the speed of stoker engine will feed just enough fuel to keep fuel bed at a proper thickness, and that when plunger 12 is at other end of its travel stoker speed will be such as to maintain the fuel bed at its proper thickness under these conditions of draft. It follows that any intermediate points of travel of plunger 12 will give a proportionate stoker speed to maintain the fuel bed at a proper thickness.

On the drawing is shown the control valve of a well known stoker of the underfeed ram type. The result would be the same if connection were made to a chronometer valve controlling speed of engine-driven 110 stokers.

We claim:

In a regulator of the class described, an inverted cup piston, a liquid sealed cylinder for the same said piston having an open connection for connection to the furnace to be controlled, a fulcrumed beam, means connecting the piston to one side of the beam, an adjustable counter weight connected to the other side of the beam, a hydraulic work-

ing cylinder for operating a furnace control member, a pilot valve for said operating cylinder, said valve being reversible and having a neutral position, said beam being normally balanced when a predetermined gas pressure acts upon said cup piston, said pilot valve being connected to said beam and being in neutral position when the beam is normally balanced, and spring means for

said beam to afford increasing resistance for increasing deflection of the beam either way from normally balanced position, said liquid sealed cup piston serving as a dashpot to steady the weighted beam against vibration.

In testimony whereof we affix our signatures.

LOUIS P. FESSENDEN.
HARRY R. ELLIS.
